H. W. RUSS

WOOD HEEL BLANK HOLDER

Filed Oct. 12, 1922

Inventor,
Harley W. Russ,
by *John Hammann*
Atty.

UNITED STATES PATENT OFFICE.

HARLEY W. RUSS, OF HAVERHILL, MASSACHUSETTS.

WOOD-HEEL-BLANK HOLDER.

Application filed October 12, 1922. Serial No. 594,115.

To all whom it may concern:

Be it known that I, HARLEY W. Russ, a citizen of the United States, a resident of Haverhill, county of Essex, State of Massachusetts, have invented an Improvement in 5 Wood-Heel-Blank Holders, of which the following is a specification.

This invention relates to certain improvements in means for manufacturing wood 10 heels, and more particularly to the blank holding means used in performing the various operations which are necessary in producing the finished heel, two of the more important of which are the operations of 15 "grooving," which consists in forming the breast surfaces, and "turning," which consists in shaping the sides and back. A machine for performing the grooving operation is illustrated in my pending application 20 Serial No. 587,893, and, incidental to the description thereof, a form of jack is illustrated, which is provided with two projecting pins, in the clamp member which engages the base, arranged to enter two holes 25 which have previously been bored in the base portion of the blank.

While this arrangement possesses all the advantages stated, in that the blank is held 30 in precisely the same relation to the operating parts in each machine in which the blank is placed, so that the operations will be performing in exact predetermined relation to 35 each other, yet the operation of boring the holes in the blank is a separate operation, which adds materially to the cost of manufacture.

The object of the present invention is to 40 provide means whereby all the advantages incident to the use of the positioning pins may be retained, but the cost of preparing the blank for the reception thereof may be eliminated.

I accomplish this object by providing the member of the clamp, or jack used to hold 45 the blank in performing the grooving operation with means which act to form positioning recesses in the blank, by the action of forcing the clamping members into clamping engagement therewith, so that, when the 50 blank is removed therefrom, and placed in another machine, which is provided with a holding means similar to that employed in the first machine, the blank will be positioned therein in the same relation to the 55 tools which are to operate thereon to per-

form the next operation, as to the tools which performed the preceding operation.

For a further disclosure of the invention reference is made to the accompanying drawing in which:

Fig. 1 is a side elevation of a heel-blank-clamp embodying my invention.

Fig. 2 is a plan view of the base-engaging member.

Fig. 3 is an end view thereof. 65

Fig. 4 is a sectional view at line 4—4 of Fig. 2.

Fig. 5 is a detail view of one of the supporting and guiding devices of the blank gage table. 70

Figs. 6, 7 and 8 are detail end, side and sectional views, respectively, of one of the positioning recess forming pins.

Fig. 9 is a detail view of a form of positioning pin which is preferably employed. 75

Figs. 10 and 11 are sectional views of a wood heel blank before and after it has been clamped.

The particular heel-clamp or jack illustrated is of well known form, and comprises 80 a main support 2, having an upright 4 thereon, to which the clamp member 6, for the top of the blank, is attached, a clamping screw 7 being arranged in an arm 8 on the upright to force the member 6 into clamping engagement with the top side of a blank supported therebeneath. 85

A flat rectangular shaped plate 9, preferably of wood, is mounted on the support 2, and provides an engaging face for the blank 90 on its upper side. A pair of cross bars 10 and 12 are rigidly secured to the support 2, beneath the plate 9, and extend transversely thereof, and a table 14, in the form of a flat plate having an angular recess which receives the plate 9, is supported thereon in a horizontal position by means which permit the same to move vertically to a limited extent, said means comprising three vertical guide pins 16, which are fixed in the table 100 14, two of which are slidable in the cross bar 12 and the third in the cross bar 10, and three vertical screws 18 which extend through the table and are threaded in the cross bars adjacent said pins, said table being slidable 105 on the screws and supported by springs 20 thereon, which act normally to hold the table in contact with the heads thereof. The right angularly disposed edges of the table 14, which are adjacent the plate 9, are held in 110

2
close proximity to the edges of the latter and gage plates 22 and 24 are mounted on the upper side of the table 14, and are provided with faces at their front edges for 5 engaging the back and one side face of a wood heel blank, said gage plates being adjustable to and from said edges, respectively, of the table 14, and, being held at a distance therefrom, and in parallel relation, respectively, thereto, depending on the size of the blank, so that, when a blank is placed in position on the base member, its rear side will be engaged with the face of the gage 10 22 and one side with the face of the gage 15 24, and its under side portions adjacent said sides will rest on the upper surface of table 14.

A pair of metal pins 25 are mounted in upright position at a suitable distance apart, 20 in sockets formed to receive the same in the support 2, said pins extending through the wooden plate 9, and each having a pointed end-portion 25^a, preferably of conical form, which projects beyond a shoulder 25^b held 25 flush with the upper surface of the plate 9. The extreme end of each end portion is truncated and capped out centrally, as shown in Figs. 6 and 8, to provide a sharp cutting edge 25^c at the extreme end of said conical portion. Said projections are of such a length, or said table 14 is so adjusted by means of the screws 18, that the edges 25^c are in the plane of the upper surface of the table, so that, when a heel blank is placed in position 30 on the latter, it will also be supported on said edges. The arrangement of the pins 25 with relation to the gages, 22, 24 is such that when the blank is placed in position on the table 14, with its edges engaging the faces 35 of said gages, the ends of the pins will engage the base face of the blank in its middle longitudinal line.

With the above described construction, when a blank, as α in Fig. 10, is placed in 40 position on the table 14, as shown in Fig. 1, and the top member is forced down into engagement therewith, the table 14 will be pressed downward with the blank, thiereby causing the blank to be pressed down on the 45 pointed end-portions of the pins 25 and causing the formation of correspondingly shaped conical recesses, as α' , therein, so that, after the blank has been operated on, and removed ready to be placed in another 50 machine, the recesses thus formed will enable the blank to be exactly positioned for the next operation. Preferably, the clamp 55 for holding the heel for the next operation will be provided with pins, as 26, shown in Fig. 9, which are similar to the pins 25, and will be located in precisely the same relation as said pins 25, their ends being preferably somewhat rounded as shown, so that the 60 blank may be placed thereon with greater 65 facility.

The particular formation of the pins 25, at their ends, is advantageous for the reason that their end edges 25^c will cut the fibers of the wood as they are pressed therein, while, if the ends were sharply pointed, there would 70 be a tendency to move the blank sidewise out of position thru variations in hardness of the fibers, and as the fibers are actually cut, and a portion thereof is forced inward, the possibility that the fibers will spring back and 75 refill the recess is greatly lessened.

During the grooving or turning operation on the blank, the pins are also effective in preventing sidewise movement of the blank between the clamp members.

When the pressure on the blank is removed, the springs 20 beneath the table 14 will lift the latter and free the blank from the pins 25.

With the above described construction it 85 will be apparent that the formation of the positioning recesses will be merely incident to the operation of clamping the blank in position and therefore are formed without expense.

I claim:

1. A wood heel blank holder comprising an upwardly facing clamp member having a pair of upwardly projecting pins constructed and arranged to form positioning 65 recesses in the blank as it is clamped on said member, a vertically movable table horizontally disposed over said member adjacent said pins and having a blank-supporting face on its upper side, yieldable means for sustaining said table with its face adjacent the level of the upper ends of said pins and means extending above said face to hold the blank thereon in position to permit the pins to penetrate the same at predetermined points as the blank is clamped.

2. A wood heel blank holder comprising an upwardly facing clamp member having a pair of upwardly projecting pins constructed and arranged to form positioning recesses in the blank as it is clamped against said member, a vertically movable table horizontally disposed over said member adjacent said pins and having a blank supporting face on its upper side, yieldable means for sustaining said table with its face at the level of the upper ends of said pins and means arranged to engage a side and an end of the blank to position the same on said face with relation to said pins and to hold it in positioned relation as it is forced into clamped position.

3. A wood heel blank holder comprising an upwardly facing clamp member, a pair of vertically projecting metal pins mounted on said member and having end portions adapted to be forced into the blank as it is clamped, a vertically movable table arranged over said member adjacent said pins and having a horizontally disposed blank-sup-

porting face, yieldable means for sustaining said table with its face at the level of the upper ends of said pins, and blank positioning means on said table for holding the 5 blank on its face in predetermined relation to said pin as it is forced to clamped position.

4. A wood heel blank holder comprising an upwardly facing clamp member, a pair 10 of vertically projecting metal pins mounted on said member and having end portions adapted to be forced into the blank, as it is clamped, a vertically movable table arranged over said member adjacent said pins and 15 having a horizontally disposed blank-supporting face, spring actuated means for sustaining said table with its face at the level of the upper ends of said pins, and gages mounted for independent horizontal adjustment 20 to engage a side and an end of a blank on said face and position it in relation to said pins and to hold it in positioned relation as it is clamped.

5. A wood heel blank holder comprising 25 a clamp member adapted to engage the base side of the blank, a pair of metal pins mounted therein having positioning-recess forming end portions at their upper ends, a table having a blank-supporting face and 30 blank-positioning means thereon, and spring

actuated means for normally supporting said table with its said face on a level with the upper ends of said pins, said means being adapted to yield to permit the blank to be clamped against said member and forced 35 onto the end portions of said pins and to lift the blank when it is unclamped.

6. A wood heel blank holder comprising a clamp member having a horizontally disposed clamping face on its upper side arranged to engage the base surface of a blank, 40 a pair of metal pins mounted in said member and having tapering end-portions projecting vertically upward beyond the face thereof, a table having angularly disposed 45 gage-faces thereon arranged to engage adjacent sides of the blank, to position the same in predetermined relation to said pins, and having a blank-supporting surface in front of said faces, means for yieldingly supporting said table with said surface at the level of the ends of said pins and means for forcing the blank downwardly, to clamp 50 it against the face of said member, and force it onto the end portions of the pins, to form 55 a pair of positioning recesses therein.

In testimony whereof, I have signed my name to this specification.

HARLEY W. RUSS.
